DESIGN FOR A COMBINED FENCE AND GATE

Luigi Vecchio, Syracuse, N. Y.

Application December 19, 1947, Serial No. 143,242

Term of patent 14 years

(Cl. D28—1)

To all whom it may concern:

Be it known that I, Luigi Vecchio, a citizen of the United States, residing at Syracuse, in the county of Onondaga, State of New York, have invented a new, original, and ornamental Design for a Combined Fence and Gate, of which the following is a specification, reference being had to the accompanying drawing, forming a part thereof.

In the drawing:

Fig. 1 is a top plan view of the combined fence and gate, showing my new design.

Fig. 2 is a front elevation, and

Fig. 3 is an end elevation of the combined fence and gate.

I claim:

The ornamental design for a combined fence and gate, as shown.

LUIGI VECCHIO.
